UNITED STATES PATENT OFFICE.

LEE W. BARBER AND EDWIN W. WEBB, OF CHICAGO, ILLINOIS, ASSIGNEES TO STAND-
ARD CAR TRUCK COMPANY, OF CHICAGO, ILLINOIS, A CORPORATION OF NEW
JERSEY

ROLLER SIDE BEARING.

1,128,400.

Specification of Letters Patent. Patented Feb. 16, 1915.

Application filed May 8, 1914. Serial No. 837,129.

To all whom it may concern:

Be it known that we, LEE W. BARBER and EDWIN W. WEBB, citizens of the United States, residing at Chicago, in the county of Cook and State of Illinois, have invented certain new and useful Improvements in Roller Side Bearings; and we do hereby declare the following to be a full, clear, and exact description of the invention, such as will enable others skilled in the art to which it appertains to make and use the same.

Our invention has for its object to provide an extremely simple and highly efficient roller side bearing for railway cars, and to such ends, generally stated, the invention consists of the novel devices and combinations of devices hereinafter described and defined in the claims.

The invention is illustrated in the accompanying drawings wherein like characters indicate like parts throughout the several views.

Referring to the drawings: Figure 1 is a plan view showing the improved side bearing; Fig. 2 is a side elevation of the same; Fig. 3 is a plan view of the roller caging or spacing frame removed from the bearing; Fig. 4 is a section taken approximately on the line $x^4 x^4$ on Fig. 1, some parts being broken away; Fig. 5 is a view corresponding to Fig. 4, but illustrating a slightly modified construction; and Fig. 6 is a fragmentary view in horizontal section taken approximately on the line $x^6 x^6$ on Fig. 5.

The numeral 1 indicates the casting or housing of the side bearing, and which is preferably of channel form, formed with laterally spaced vertical flanges that confine the rollers 2 for radial travel within the limits of their movement. Preferably, the housing 1 is provided on its bottom with a flat steel bearing plate, upon which the rollers 2 directly run. In their ends, the rollers 2 are provided with axial indentations affording seats for trunnions 4 formed on and projecting inward from the laterally spaced arms of a roller spacing cage 5, the sides of which, as shown, are connected by an integral bar located between the rollers. The cage 5 is preferably made of malleable iron, steel or other metal which is capable of being bent, so as to effect the engagement of the trunnions 4 with the seats in the ends of the rollers. Both the cage and the rollers 55 are adapted to be inserted into the housing

through one end thereof. The laterally spaced flanges of the said housing are provided with inturned ribs 1^a that overlie the sides of the cage 5 and prevent the same, and the rollers from jumping out of working position. A centering spring is provided for yieldingly holding the roller cage 5 in a centered or intermediate position, and for restoring the same to normal position, when the rollers are relieved from the pressure of the load, so that the said rollers will always start from a proper initial centered position when the load is thrown thereon, and the car moved from a straight line onto a curve, or vice versa. One form of centering spring is shown in Figs. 1 to 4, inclusive, and another form is shown in Figs. 5 and 6.

Referring first to the first noted centering device, the numeral 7 indicates a spring having extended arms and a coiled portion 7^a, which latter is telescoped over a raised boss 1^b on the housing 1 and is held in position by a washer 8 and rivet 9. The lower and relatively short arm of this spring 7 closely fits a notch 1^c formed in the adjacent side of the housing 1, while the upper and relatively long arm of said spring works freely through an elongated slot 1^d in the said housing wall, and engages between a pair of depending lugs 5^a on the cross bar of the roller cage 5.

It is important to note that the free end of the spring 7 is attached to the intermediate portion of the connecting bar 5 of the roller spacing cage. This applies the force of the spring to the central portion of the cage and prevents the spring from tending to throw the cage out of its proper arc of movement, and hence, does not cramp the cage within the housing.

The centering device shown in Figs. 5 and 6 comprises simply a flat spring 10, that works through and closely fits a slot 11 formed in the adjacent wall of the housing 1 and has its outer end fixed between lugs 12 on the housing, as shown, by means of a split key 13, while the inner and free end of the said spring works between the lugs 5^a of the said roller cage 5. The centering device shown in Figs. 5 and 6 is probably the best form of the two illustrated, but either form will yieldingly center the rollers and cage.

In the construction illustrated, all of the load and bearing is taken in a crushing strain on the rollers, and no part thereof,

on the trunnions or pivotal connections between the rollers and spacing cage. It is a well known fact that the load is never simultaneously carried on the roller side bearings on opposite sides of the car, but will be alternately thrown from one side to the other, depending on the load and the direction of the curve. Where roller centering devices are not provided, the rollers are liable to be worked out of proper initial working position, due to the fact that the rollers, when relieved of the load or curve, may be left at one extreme, and the next time the load is delivered onto the same, will be carried farther in the same direction, away from a centered or intermediate position. The centering devices automatically bring the rollers to centered or intermediate initial positions when relieved from load, so that they will stand always from the right point when caused to carry the load.

What we claim is:

1. A roller side bearing comprising a body member having a roller bearing surface, a plurality of rollers mounted to travel on said bearing surface, a roller spacing cage com-

prising laterally spaced arms to which said rollers are journaled and having a bar connecting them between said rollers, and a centering spring anchored to said body member with its free end extended and attached to the intermediate portion of the connecting bar of said cage. 30

2. In a roller side bearing, the combination with a body member having a roller bearing surface, of a plurality of rollers mounted to travel on said bearing surface and provided with axial trunnion seats, and a roller spacing cage formed by laterally spaced arms and an intermediate connecting 40 bar, the said arms, at their ends, completely separated and having trunnions adapted to be engaged with the axial seats of said rollers by springing of the said arms. 45

In testimony whereof we affix our signatures in presence of two witnesses.

LEE W. BARBER.
EDWIN W. WEBB.
